CLAIM

The ornamental design for a pedal for a bicycle, as shown and described.

DESCRIPTION

FIG. 1 is a perspective left side view of a pedal for a bicycle showing my new design;

FIG. 2 is a perspective right side view thereof;

FIG. 3 is a top plan view thereof;

FIG. 4 is a right side elevation view thereof.

The bottom of the pedal is substantially plain and unornamented.

FIG. 1

FIG. 2

FIG. 3

FIG. 4
